GRIPPING MECHANISMS FOR WIRE-TYING MACHINES

Frank H. Lamb, Hoquiam, Wash., assignor to Ovalstrapping Inc., Hoquiam, Wash., a corporation of Washington

Application April 25, 1955, Serial No. 503,703

4 Claims. (Cl. 254—51)

The present invention relates to hand-operated wire-tying machines and is particularly directed to an improved wire-end gripping mechanism for use on such machines.

Conventional wire-end gripping mechanisms, while generally satisfactory, occasionally prematurely release the gripped wire-end, particularly when operated by unskilled persons. Premature release is not only an annoyance and a time-waster since it calls for repetition of the tensioning procedure, but it is also definitely dangerous. The danger of course lies in the fact that the prematurely released wire-end may, due to the tensioned condition and springy nature of the tying wire, fly out and injure the operator.

Another disadvantage of some prior arrangements is that the released wire-end is left projecting outwardly from the tied package, resulting in hand injuries or damage to other packages. To overcome this second disadvantage various proposals have been put forward, mainly based on "kinking" the wire to direct the terminal portion thereof downwardly towards the package at a small angle to the plane of surface where the tie is located. Many of these proposals have failed to give consistently satisfactory results, however, since, while they usually successfully "kink" the wire-end, the "kink" produced is not infrequently destroyed during the release of the gripping jaws preparatory to withdrawing the machine from the "tie."

After considerable study and experimentation, I have discovered that these disadvantages could be entirely avoided by resort to a sliding finger member arranged for interpositioning between (a) the element carrying the lower gripping surface, and (b) a special stop member, as said gripping surface is carried towards its final gripping position.

While the discovery just mentioned is the basis for the present invention, the essence of the invention would be better defined as follows: a wire-end gripping mechanism for a wire-tying machine which includes a flat vertical surface for the mounting of said mechanism; said mechanism comprising a fixed stub shaft extending outwardly from said surface at right angles thereto; a generally rectangular anvil-carrying block rotatably mounted on said stub shaft; an anvil integral with said block extending outwardly from the base of said block substantially at right angles thereto; first stop means extending outwardly from said machine on one side of said block and adjacent the bottom thereof to limit rotary movement of said block in one direction; second stop means secured to said flat vertical surface on the other side of said block and adjacent the bottom thereof to limit the rotary movement of said block in the other direction; biasing means attached to the upper end of said block to urge the anvil-carrying block to rest against said second stop means; a spring-loaded finger slidably mounted on said flat vertical surface above said second stop means and arranged to slide into an intervening position between said block and said second stop means when said block has been rotated, against the action of said biasing means, to a point im-

2

mediately adjacent said first stop means; an operating lever rotatably mounted on said stub shaft outwardly of said block; a wire-gripping element secured to the lower end of said operating lever, said element having a projecting portion which extends outwardly from said operating lever on the side thereof adjacent said second stop means; and a projection on said slideable finger located for lifting engagement by the projecting portion of said wire-gripping element, whereby said spring-loaded slideable finger may, through actuation of said operating lever, be forced out of the said intervening position despite the spring-loading of the finger.

In drawings illustrating the presently preferred embodiment of the invention:

15 Figure 1 is a front elevation showing the wire gripping mechanism in its initial position.

Figure 2 is a view similar to Figure 1 except for the fact that it shows the mechanism in the wire gripping position.

20 Figure 3 is an exploded perspective view showing some parts which are not adequately illustrated by Figures 1 and 2 alone.

Figure 4 is a perspective view of the operating lever, and

25 Figure 5 is a fragmentary detail showing portions of the operating lever and anvil-carrying block.

In these drawings, reference character 10 generally indicates a wire-tying machine. The drawings only show the end of the machine where the invention is applied 30 since the remainder of the machine may be of quite conventional construction and its inclusion would entail an undesirable cramping of the scale of the drawings. The illustrated end of the machine is provided with a flat vertical surface 11 for the mounting of the novel wire-end gripping mechanism. A fixed stub shaft 12 extends outwardly from surface 11 at right angles thereto. An anvil-carrying block 13 of generally rectangular vertical and transverse cross-section is rotatably mounted on stub shaft 12 by virtue of a bore which extends through the block in the generally central region thereof. An anvil 14, integral with the block 13, extends outwardly from the base thereof, the anvil being disposed substantially at right angles to said block.

Since anvil 14 is to play the part of the lower gripping element, the shape of the upper surface of the anvil is important. From Figure 3 it may be noted that the anvil's upper surface consists of three flat regions each featuring a different slope. To be more specific, a flat triangular region 15, which is substantially horizontal 45 when the block 14 is in its initial (Figure 1) position, extends outwardly from block 14; a flat triangular region 16 slopes downwardly and towards the centre of the machine 10 at a marked angle to region 15; and a flat region 17 slopes downwardly and outwardly from region 15. The reasons for providing the differently sloped regions 15, 16 and 17, will be more fully pointed out later on.

The wire-tying machine 10 has a conventional slotted arrangement 18 for holding the overlapped lengths of 50 wire during their intertwisting to form the wire "tie." The end wall of arrangement 18 which lies nearest the gripping mechanism has been labelled 19 and constitutes a stop means limiting rotation of the anvil-carrying block 13 in one direction. This end wall 19 which acts as a stop is referred to as a "first stop means" in the accompanying claims.

A second stop means is provided to limit rotation of the anvil-carrying block 13 in the other direction. This second stop means, which has been labelled 20 in the drawings, is adjustably, removably, secured to flat surface 11 and extends outwardly therefrom at a point adjacent the bottom of the block 13 and on the opposite

side of the block from the stop 19. Stop 20 is a rectangular block which is pointed at one end, and is "pointed" downwardly at an angle of about 30 degrees to horizontal. The upper of the two faces which form the point has been labelled 21 and is seen to be generally vertically disposed. Attention is invited to the recessing of the upper surface of the stop 20 to provide a more sharply sloped region 22 which leads into point-forming face 21 but is only located in the outermost half of the upper surface of the stop block.

A tension spring 23 is stretched between a fixed pin 24 extending outwardly from surface 11 and a pin 25 extending upwardly from the upper end of anvil-carrying block 13. Tension spring 23 is a biasing means which urges anvil-carrying block 13 to rest against surface 21 of stop means 20, the so-called "second stop means."

A spring-loaded finger 26 is slidably mounted on the surface 11 above second stop means 20 and is disposed at an angle of approximately 60 degrees to horizontal. The slidable mounting is achieved by means of a longitudinal slot 27 which extends through the finger at the upper end thereof and a fixed pin 28 which extends outwardly from surface 11 and is provided with an enlarged head to retain the finger against surface 11. The spring-loading is effected by means of a compression spring 29 set in a central bore in the finger and bearing against the base of said bore and the pin 28. Spring 29 urges opposite sides of the lower end of the finger 26 to contact the second stop means 20 and the adjacent side of the block 13. A pin 30 projects outwardly from finger 26. The function of pin 30 will appear later on when the functioning of the slidable finger is being described.

An operating lever 31 is rotatably mounted on stub shaft 11 by means of a transverse bore 31a extending through the lower portion 32 of the lever. Lever 31 is provided with a spherical handle 33. The lower portion 32 of operating lever 31 is of rectangular transverse cross-section. A rectangular recess 34 is provided on the inner side of the lever in the corner thereof nearest stop means 20. The cutting of recess 34 is effected so as to leave a pin-like element 35 for the mounting within the recess of a generally rectangular wire-gripping element 36 having gripping teeth along its lower edge 37. Some clearance, as indicated at 38, is left between the wire-gripping element 36 and the confining walls of the rectangular recess 34, so that the element is permitted a few degrees of rotation about its supporting pin 35. Wire-gripping element 36 has a projecting portion 39 which extends beyond the side of the operating lever 31 on the side thereof adjacent second stop means 20. Projecting portion 39 is bluntly pointed and has a straight-line upper edge 40.

Above the bore 31a, a bore 41 extends through the operating lever 31 at right angles to the bore 31a (see Figures 3 and 5). A tension spring 42 is accommodated by bore 41 and is stretched between a screw 41a set in the operating lever at one end of the bore and a hooked element 43 which is attached to the opposite end of the spring and seated in a retaining recess 44 provided in anvil-carrying block 13. It can readily be seen that tension spring 42 is a biasing means which urges the operating lever 31 to rotate about the stub shaft 12 in a direction which brings the toothed lower edge 37 of wire-gripping element 36 into contact with the anvil 14.

A stop 45 is rigidly secured to surface 11 at a point substantially vertically above first stop means 19, and functions to limit rotation of the operating lever 31 in one direction. Rotation of the operating lever in the other direction is limited by first stop means 19 which acts through anvil-carrying block 13 and wire-gripping element 36 to impose the limitation.

Having provided a full structural description of one embodiment of my invention, I will now proceed with a description of its operation.

A length of tying wire sufficient to tie a given package is drawn off a suitable supply reel and caused to encircle the package with the free end of the wire introduced in the novel end-gripping mechanism, with two portions of the wire extending beside one another through the slotted arrangement 18 where the tying mechanism proper is located, and with the reel end of the wire passing through a tensioning mechanism (not shown). The point of interest here will of course be the mode of introduction of the wire-end into the gripping mechanism. The wire-end is passed along the flat region 15 of anvil 14, with the side of the wire pressing against the outer surface of block 13, until the extreme end of the wire contacts recessed portion 22 of stop means 20. It will be understood that during this step the anvil block 13 bears against stop means 20, and is held there by spring 23. It will also be appreciated that the introduction of the wire-end through the gripping mechanism forces a small amount of rotation of the operating lever 31 (in the opposite direction to the arrow B), since the introduction involves raising wire-gripping element 36, which in turn causes rotation of the operating lever, against the action of the spring 42, which normally urges element 36 into contact with surface 15 of anvil 14. The gripping teeth on the lower edge 37 of gripping element 36 are directed to permit sliding of the wire in the direction of step 20, but to bite into the wire when it is drawn in the opposite direction. Such teeth are well-known and need no further description.

Having thus inserted the wire's end, the course of wire which encircles the package may be tensioned about the package. The tensioning procedure involves unitary rotation of the lever 31 and the block 13 until they are both halted by the anvil-carrying block striking against first stop means 19. As this movement of the anvil-carrying block takes place, the spring-loaded finger 26, whose lower end bears against both the anvil block and the inclined upper surface of stop means 22, slides downwardly under the influence of the spring 29 and interpositions itself between the anvil block and the substantially vertical face 21 of the stop block 20. It will be noted that the finger is, in effect, a spring-powered wedge which is driven home as the anvil block meets the stop means 19, and prevents rotation of the anvil block in the opposite direction until such time as the finger is lifted out of its wedging position. It is perhaps now timely to point out that the leading edge of the finger 26 is cut away at 46 to assist this sliding-wedging action.

During the tensioning procedure the wire, since it is both gripped between element 36 and surface 15 of anvil 14 and confined within the slotted arrangement 18, is bent over the ridge which exists between regions 15 and 16 of the upper surface of anvil 14. The wire-end is drawn so tightly across the ridge just mentioned that a definite kink is imparted in the wire. Slippage of the gripped wire end after tensioning is virtually ruled out by the action of teeth of edge 37 in conjunction with the positioning of the anvil. In the locked position, the ridge between surfaces 15 and 16 of the anvil is raised above the course of the wire through slotted arrangement 18, and the surface 15 slopes downwardly and outwardly from said ridge, so that the more the wire is tensioned the more strongly do the teeth bite into the wire and clamp it between the gripping element and the anvil.

Once the wire has been tensioned, the conventional twisting operation would be performed to effect the tie, and the reel end of the wire would be cut-off. This would complete the operation except for release of the wire-end preparatory to withdrawal of the tying machine. The wire-end is released simply by actuating lever 31 in the opposite direction to the arrow B. Quick release is achieved since the gripping element 36 is lifted clear of the anvil while the latter is still held against stop 19. Further lifting, i. e. further rotation of the lever, causes edge 40 of gripping element 36 to contact pin 30 and

raise slidable finger 26, against the action of spring 29, out of wedging position; whereupon the anvil block 13 is immediately driven by its spring 23 into contact with stop means 20. The gripping mechanism would then be ready for gripping a new wire end. Withdrawal of the machine is facilitated by the earlier-described slope of region 17 of the anvil. The kink imparted by tensioning the wire over the ridge between anvil regions 15 and 16 is not disturbed by the releasing and withdrawing steps, and positions the wire's end in the desired safe manner.

What I claim as my invention is:

1. A wire-end gripping mechanism for a wire-tying machine which includes a flat vertical surface for the mounting of said mechanism; said mechanism comprising a fixed stub shaft extending outwardly from said surface at right angles thereto; a generally rectangular anvil-carrying block rotatably mounted on said stub shaft; an anvil integral with said block extending outwardly from the base of said block substantially at right angles thereto; first stop means extending outwardly from said machine on one side of said block and adjacent the bottom thereof to limit rotary movement of said block in one direction; second stop means secured to said flat vertical surface on the other side of said block and adjacent the bottom thereof to limit the rotary movement of said block in the other direction; biasing means attached to the upper end of said block to urge the anvil-carrying block to rest against said second stop means; a spring-loaded finger slidably mounted

on said flat vertical surface above said second stop means and arranged to slide into an intervening position between said block and said second stop means when said block has been rotated, against the action of said biasing means, to a point immediately adjacent said first stop means; an operating lever rotatably mounted on said stub shaft outwardly of said block; a wire-gripping element secured to the lower end of said operating lever, said element having a projecting portion which extends outwardly from said operating lever on the side thereof adjacent said second stop means; and a projection on said slidable finger located for lifting engagement by the projecting portion of said wire-gripping element, whereby said spring-loaded slidable finger may, through actuation of said operating lever, be forced out of the said intervening position despite the spring-loading of the finger.

2. A wire-end gripping mechanism as defined in claim 1, including stop means for said operating lever disposed generally vertically above said first stop means.

3. A wire-end gripping mechanism as defined in claim 1, including biasing means urging said operating lever to rotate in a direction which brings said gripping element into contact with said anvil.

4. A wire-end gripping mechanism as defined in claim 3, in which both said biasing means utilize a tensioned spring arrangement.
